ATTY'S.

UNITED STATES PATENT OFFICE.

ANDREW McANULTY, OF OTTAWA, ONTARIO, CANADA.

RAZOR.

1,360,423.

Specification of Letters Patent. Patented Nov. 30, 1920.

Application filed December 1, 1919. Serial No. 341,612.

To all whom it may concern:

Be it known that I, ANDREW McANULTY, a subject of the King of Great Britain, a resident of the city of Ottawa, Province of Ontario, Dominion of Canada, have invented certain new and useful Improvements in Razors, of which the following is a specification.

This invention relates to improvements in razors, and the objects of the invention are to permit of an ordinary blade razor being utilized either as a straight blade or as a safety razor, to provide means whereby the safety device may be concealed within the handle of the razor when not in use, and to facilitate attaching and detaching the safety device to the razor blade, with a minimum of time and effort.

Further objects are to permit of the safety device being adjusted relatively to the razor blade so that it will compensate for any wear of the razor blade, that is to say, the safety device will be positioned relatively to the edge of the blade in the position best adapted to allow the razor and safety device to perform the functions required of them, to give adequate clearance between the safety device and the blade when the former is not in use, and generally to adapt the razor to better perform the functions required of it.

With the above and other objects in view, the invention consists essentially of the improved construction particularly described and set forth in the following specification and accompanying drawings forming part of the same.

In the drawings:

Figure 1 is a side elevation of a straight blade razor, showing the improved safety device, part of the handle being broken away to show the means for retaining the safety device within the handle when not in use.

Fig. 2 is a side elevation of an alternative form of the safety device.

Fig. 3 is a side elevation of still another form of the safety device with the parts disconnected.

Fig. 4 is a side elevation of the safety device shown in Fig. 3 with the parts connected.

Fig. 5 is a longitudinal section of the straight blade showing the safety device in engagement therewith.

Fig. 6 is a plan view of the straight blade

razor showing the safety device located within the handle and retained in position therein.

Fig. 7 is a side elevation of a straight blade showing an alternative form of the safety device and means for securing the same disengaged from the blade.

Fig. 8 is a side elevation of that alternative form of the safety device shown in Fig. 7, showing it in engagement with the blade.

Like characters of reference refer to like parts in the several figures.

In shaving with a straight blade razor, many people use both the right and left hand, and under such circumstances the safety attachment would require to be duplicated, that is to say, one located on each side of the blade.

For descriptive purposes, however, I have only illustrated one safety device to the blade, the other being left out as it would only add to the complexity of the drawings.

In the embodiment of my invention illustrated, A represents an ordinary straight blade razor provided with a handle 10 to which the blade is hinged by a pin 11, the blade being provided on the shank with a lateral projection 12 having under cut edges.

The two portions of the handle 10 are spaced by distance piece 13 located at the end remote from the hinge pin 11 of the blade, and this distance piece has an undercut edge 14 forming a lip 15, which projects 90 inwardly and longitudinally of the handle.

Intermediate of the ends of the handle a second distance piece 16 is provided which also acts as a guide to facilitate securing the safety device B to the blade A, in a 95 manner to be made clear hereafter.

The safety device B has a serration or tooth blade portion 17 and the shank 18 arranged in parallelism with the hand and connected by an offset integral portion 19.

The safety device B is pivoted to the hinge pin 11, but is capable of longitudinal movement to a limited extent, and that end of the shank remote from the hinge pin 11 is provided with a keyhole slot 20 adjacent to which a projecting pin 21 is located to form a finger grip. The end of the blade of the safety device B remote from the hinge pin 11 is provided with a hooked end 22.

To hold the safety device B in spring engagement with the blade of the razor, there is

provided a longitudinally extending and slightly offset spring portions 23 formed integral with the shank 18, the portions 23 being made of the same material as the safety device B.

When this form of my invention is in use, it will assume the position shown in Fig. 6 when closed, the safety device B lying within the two side members of the handle 10, and the device B will have been moved longitudinally toward the distance piece 13 so that the hooked end 22 will slightly project below the lip 15 of the said distance piece thus securing safety device B within the side member of the handle 10 and permitting the blade A being used as an ordinary straight blade razor.

Should the user desire to attach the safety device B, he closes the blade A and the lower end of the shank 18 of the razor A and the shank of the safety device B will engage with the distance piece 16 and be held in the desired position, so that the laterally projecting pin 12 will register with the enlarged end of the keyhole slot 20, whereupon the finger grip 21 is engaged and the safety device B moved longitudinally relatively to the blade A, so that the hooked end 22 will thus be brought into engagement with the end of the blade A.

The undercut edges of the pin 12 will have engaged with the keyhole slot 20, thus preventing any tendency of lateral movement of the safety device B. The blade A may now be rotated outwardly from the handle 10, and in so doing the safety attachment B will also be rotated as it is now held in frictional engagement with the blade A.

The razor now of the safety type may be used with freedom, and when the user has shaved the safety device B may be detached from the blade A, to permit of the cleaning of the blade and safety device, which will then be located between the side members of the handle 10 and moved longitudinally so that the hooked end 22 will engage with the projecting lip 15, of the distance piece 13 and hold the safety device closed.

The blade A can then be rotated individually and it will be evident that the blade may be honed and stropped in the same manner as the ordinary straight blade.

After the razor has been in use some time it may happen that due to wear, grinding, etc., the blade A will become worn, and it will be necessary to make adjustment of the safety device B relatively to the blade A, and to this end I have provided the safety device B with a pair of U-shaped slots 24 in the shank 18. One of the U-shaped slots 24 is engaged with the hinge pin 11, and the other may be engaged with the projecting pin 12.

It will be evident, that if the hinge pin 11 and projecting pin 12 engage with the up-

per parallel arm of the horizontally disposed U-shaped slots, then the safety device B will overhang the cutting edge of the razor A to a certain extent.

After the blade has become worn, the hinge pin 11 and the pin 12 may be engaged with the lower parallel arm of the horizontally disposed U-shaped slots 24 thereby adjusting the safety device B relatively to the blade A, so that the serrated edge of the safety device will overhang the cutting edge of the blade to the desired extent.

In Figs. 3 and 4 a slight modification of the safety device is shown and connects in forming the device in two portions, 25 and 26, the portion 25 having a slot 27 and a projecting tongue 28, the former of which is engaged by the projecting tongue 29 on the shank 25, while the tongue 28 is designed to engage with the elongated orifice having a serrated side wall 30. By providing the serrations in the orifice 30 the tongue 28 may be engaged with any of the serrations to alter the height of the portion 26 relatively to the portion 25.

In Figs. 7 and 8 the safety device B differs from that shown in Fig. 1 by eliminating the finger grip 21 and offsetting, the end 33 of the shank of the safety device, a lever 31 is hinged on the pin 11, the said lever having a projecting arm 32 which is adapted to engage the front or rear face of the offset end portions 33.

When the device B is adapted to engage with the blade A then the arm 32 engages with the front of the offset end 33 of the shank 18.

The device B is disengaged from the blade A by moving the device longitudinally, and the arm 32 of the lever 31 is engaged with the outer face of the offset end 33 so holding the hook end 20 of the safety device B disengaged from the end of the blade A.

The blade A can be used individually or in conjunction with the safety device and the blade can be cleaned, honed, stropped, etc., with care and the safety device readily adjusted to the blade A.

As many changes could be made in the above construction and many widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

1. The combination with a straight blade 125 razor, of a safety device pivotally attached to the blade, and capable of being moved longitudinally relatively thereto, and means for securing the safety device to the blade.
2. The combination with a straight blade 130

razor, of a retaining means carried by a handle of the razor, a safety device pivoted to the blade and designed when not in use to engage the retaining means, the said safety device being movable longitudinally of the blade, and means for securing the safety device to the blade.

5. The combination with a straight blade razor, of a safety device having a serrated guard and shank pivotally attached to the razor, lateral displaceable spring members integral with the shank and coacting with the razor blade, and hook means on the safety device designed to engage or disengage with the straight blade of the razor on longitudinal movement of the safety device.

10. The combination with a straight blade razor, of a safety device having a serrated guard and a shank provided with a

20. U-shaped orifice therein, a projection carried by the safety razor blade coacting with the

U-shaped orifice, and means for pivotally attaching the safety device to the razor blade.

5. The combination with a straight blade razor, of a safety device, and laterally displaceable resilient means coacting with the razor to hold the same spaced from the safety device, means for connecting the safety device to the razor blade intermediate of the length thereof, and means for engaging the point of the safety device to the point of the razor blade.

10. The combination with a straight blade razor of a safety device capable of combined longitudinal movement and transverse movement, the safety device on longitudinal movement interlocking with the straight blade razor.

15. In witness whereof I have hereunto set my hand.

ANDREW McANULTY.
